[57] CLAIM

The ornamental design for an emergency light, as shown and described.

DESCRIPTION

The present invention relates to an emergency light to be mounted on a wall surface or the like for use and requiring no power supply. When a lever extending downward from a case is pushed, chemiluminescent light sticks accommodated in the case illuminate and a top cover for covering the front portion of the case is opened.

FIG. 1 is a front elevational view of an emergency light showing our new design;

FIG. 2 is a rear elevational view thereof;

FIG. 3 is a top plan view thereof;

FIG. 4 is a bottom plan view thereof;

FIG. 5 is a left side view thereof;

FIG. 6 is a right side view thereof;

FIG. 7 is a sectional view thereof as taken along line 7—7 of FIG. 1; and,

FIG. 8 is a front elevational view thereof in a state that a top cover is opened.
